UNITED STATES PATENT OFFICE.

WILLIAM J. LAWRENCE, OF GRENADA, BRITISH WEST INDIES.

COLLAPSIBLE BARREL.

1,371,177.

Specification of Letters Patent.

Patented Mar. 8, 1921.

Application filed November 3, 1917. Serial No. 200,213.

To all whom it may concern:

Be it known that I, WILLIAM J. LAWRENCE, a subject of the King of Great Britain, residing at Grenada, British West Indies, have invented new and useful Improvements in Collapsible Barrels, of which the following is a specification.

This invention relates to improvements in barrels.

10 In carrying out my invention, it is my purpose to produce a collapsible barrel comprising a plurality of sections one adapted to be folded in the other when not in use and when not in such folded condition may 15 be secured together by the same means that is employed for retaining the sections when the barrel is in its set up condition.

It is a further object of the invention to produce a metallic barrel comprising at 20 least one central tubular member having flanged ends which, when meeting are connected together, and the outer flanges are designed to be co-engaged by flanges upon the inner ends of the substantially frusto-conical members comprising the end sections of the barrel, all of the flanges being provided with alining openings to receive securing elements, the said flanges protecting the body of the barrel when the barrel 25 is either in its set up or collapsed condition.

It is a still further object of the invention to produce a collapsible barrel wherein the sections comprising the same when not in use may be employed for other purposes 30 than that of a barrel, all of the sections having their ends provided with outturned continuous flanges which, may, if desired, receive therebetween partition plates, so that merchandise of different characters 35 may be readily received in the separate compartments of the barrel, and the said compartments, as stated, when desired, may be employed as separate utensils or holding vessels.

40 Other objects and advantages will appear as the nature of the invention is more fully understood, reference being had to the accompanying drawing, in which there is illustrated a simple and satisfactory reduction 45 of the improvement to practice, and in which drawing,

The figure illustrates an elevation of the improved barrel with parts broken away and parts in section.

As shown in the drawing, the body of the 55 barrel is constructed of a plurality of annular members 40, two being shown, each having its opposite edges flanged. The flanges 40 of the annular members are arranged one over the other and these flanges 60 are provided with spaced openings to receive the threaded parallel ends of substantially U-shaped bolts 51, the ends of the said bolts being engaged by nuts 52. The outer flanged portions of the annular members 65 40 are formed with continuous extensions 53 having inturned portions or flanges which are contacted by flanges 54 upon the outer or end sections 55 of the barrel. These end sections are in the shape of hollow 70 truncated cones, and are of a size to fit one within the other when the sides are collapsed. The flanges 54 are secured to the outer members 40 comprising the body of the barrel by elements 56. 75

From the foregoing description when taken in connection with the accompanying drawings, the simplicity and advantages of the construction, will, it is thought, be apparent without further detailed description. 80

Having thus described my invention, what I claim is:

A knock-down barrel comprising body and end portions, said body including a plurality of superimposed annular members having their ends flanged and the flanges of the said members contacting and removably connected, the outer flanges of the end body members having continuous extensions 85 provided with inturned portions, the end members each comprising a member flared from its outer to its inner end and the inner and widened ends thereof being flanged and removably connected to the 90 outer flanges of the body sections, the outer or mouth portions of the ends being flared, and flanged heads received in the said mouth portions of the ends and removably secured thereto. 95

100 In testimony whereof I affix my signature.
WILLIAM J. LAWRENCE.
